UNITED STATES PATENT OFFICE.

GUSTAV HALVORSEN-PANDE, OF CHICAGO, ILLINOIS, ASSIGNOR OF ONE-HALF TO
FRANCIS J. CUSHING, OF CHICAGO, ILLINOIS.

CHUCK.

1,115,310.

Specification of Letters Patent. Patented Oct. 27, 1914.

Application filed February 24, 1914. Serial No. 820,658.

To all whom it may concern:

Be it known that I, GUSTAV HALVORSEN-PANDE, a citizen of the United States, residing at Chicago, in the county of Cook and State of Illinois, have invented certain new and useful Improvements in Chucks, of which the following is a specification.

My invention relates more particularly to means for utilizing the rotary movement imparted by the spindle for feeding the chuck, the rate of feed being under ready control by the hand of the operator.

In the accompanying drawings and in the following specification, I disclose two preferred forms of my invention. In the simpler of these forms provision is made only for the manual control of the downward or working feed of the drill or tool. In the second form of the invention disclosed, provision is made for not only utilizing the rotation of the spindle for the downward working feed of the chuck but also for the reverse feed for lifting the tool from the work when it is finished or when for any reason it is desired to interrupt the work of the tool. These two forms of the invention are specifically described for the purpose of exemplification but it is to be understood that my invention is not limited by the disclosure but is set forth in the following claims in which I have endeavored to distinguish it from the prior art so far as known to me without, however, relinquishing or abandoning any portion thereof.

In the accompanying drawings, Figure 1 is a vertical longitudinal section through the center of the simpler form of my invention, parts, however, being shown in elevation; Fig. 2 is a side elevation of one of the members thereof; Fig. 3 is a vertical central longitudinal section through one of the members which is shown in elevation in Fig. 1; Fig. 4 is a side elevation of a member shown in section in Fig. 1; Fig. 5 is a side elevation of another member shown in section in Fig. 1; Figs. 6 and 7 are a side elevation and a transverse section respectively, the latter on the line 7-7 of Fig. 6, of the clamping jaws forming a part of the tool; Fig. 8 is a central longitudinal section through the second exemplification of my invention, parts being shown in elevation; Fig. 9 a transverse section upon the plane of the line 9-9 of Fig. 8 and Fig. 10 a section on the line 10-10 of Fig. 8.

Each part is identified by the same symbol of reference wherever it occurs in the several views.

Turning first to the simpler form of the invention shown in Figs. 1 to 7 inclusive, it will be seen that the driving member 8 (Figs. 1 and 2) comprises a rotary circular head formed with a nut 9 and a threaded bore (see dotted lines Fig. 1) in which latter the spindle 11 of the screw press is fitted, the nut serving to hold the member against rotation when being screwed upon the spindle. A squared shank 12 is formed integral with the head 8 and when the tool is assembled has a sliding connection with a jaw-carrier 13 which is formed with a longitudinal passage 14 also square in cross section to fit said shank. The lower end of the shank is cylindrical for a purpose which will appear. The bore of the jaw carrier terminates short of the lower end thereof. The jaws may be of any desired form and are shown as of an ordinary type and secured to the carrier in the usual manner. For this purpose the latter is formed with an angular recess or channel 15 which receives the upper ends of the jaws 16, 16 which are or may be suspended from a curved retainer 17 fitting in grooves 18 in the lower end of said jaw-carrier. By this means the jaws are loosely suspended so as to be capable of relative movement and are retained in channel 15 and forced together when it is required to clamp a tool therein by a sleeve 19 internally threaded to engage a thread 20 upon the exterior of the jaw-carrier 13. At its lower end the bore of the sleeve 19 is contracted as at 21 to coöperate with the convex outer surfaces 22, 22 of the jaws so that when said sleeve 19 is fed upward with respect to the jaw-carrier it engages the exterior surfaces of the jaws and forces them together. In order to feed the sleeve 19 upwardly with relation to the jaws and carrier it is formed with an external bulbous enlargement 23 which may be grasped by the hand to prevent the rotation of said sleeve, whereupon the continued rotation of the jaw-carrier by the spindle and driving member causes the sleeve to be fed upward by reason of its threaded engagement with the jaw-carrier referred to above. This construction of clamping jaws and operating mechanism is, as stated above, old in the art and I make no claim thereto.

The provision for automatically feeding the jaw-carrier which constitutes the novel feature of my invention will now be described. The upper end of the jaw-carrier is 5 enlarged and threaded as at 24, the thread engaging an interior thread upon a handle sleeve 25 which surrounds both the jaw-carrier and the clamping sleeve 19. Obviously the thread between the jaw carrier and the handle sleeve is right or 10 left handed according to the direction in which the chuck is to be turned. If it is to be turned as usual counterclockwise a right hand thread is required between the 15 elements specified. If, however, the spindle is to be turned in a reverse direction the thread must be left handed. In the accompanying drawings I have shown the thread as left handed. The direction of the rotation will of course depend upon the direction 20 of the cutting edge of the tool employed. The upper end of the sleeve 25 is provided with a pair of screws 26, 26 which extend inward and engage a groove 27 in the driving head 8 whereby longitudinal movement 25 between the parts is prevented but rotary movement allowed. The exterior of the sleeve 25 is formed to be readily grasped by the hand to prevent rotation and when so 30 held the jaw-carrier 13 revolves with relation thereto and by reason of the threaded engagement between these parts is fed downward. Thus by preventing or retarding the rotation of the hand sleeve 25 the chuck with 35 the tool clamped therein may be fed downward and the speed of feed may be regulated to a nicety.

The shank 12 as above stated is made cylindrical at its lower end 28, the length of 40 the squared portion being such that the jaw-carrier is fed downward until the enlarged threaded portion thereof reaches substantially the end of the sleeve 25. When this occurs and the squared portion of the shank 45 is clear of the bore 14 the driving member is free to revolve without turning the carrier so that further feeding operation ceases notwithstanding that the sleeve 25 may be still held from rotation. In fact when this point 50 is reached rotation of the carrier ceases altogether. The carrier, however, can be returned into engagement with the squared shank 12 by holding it stationary and revolving the sleeve 25, it being necessary of 55 course that the carrier be angularly adjusted to the position in which the shank 12 may enter the same.

Referring now to the exemplification of the invention shown in Figs. 8, 9 and 10, it 60 may be repeated that the purpose of this form as distinguished from that just described is to provide for not only the downward feed of the drill or tool but the withdrawal thereof from the work when desired. 65 The jaws 16, 16 and the means for forcing

them into engagement with the tool are or may be the same in this form of the device as in that already described and further reference thereto is therefore unnecessary. The sleeve 25' has the same threaded engagement 70 with the jaw-carrier as in the above-described modification, and therefore by holding the same against rotation the downward feed of the drill may be accomplished in the same way. The driving member 8' is formed 75 with the usual threaded cavity for receiving the spindle 11 of the press and is provided with a sleeve 30 having a cylindrical exterior fitted over the squared shank and secured thereto for a purpose which will presently 80 appear. The sleeve 25' is formed with an internal flange 31 at its upper end upon which is formed or secured a gear 32 which when the parts are assembled is journaled upon the sleeve 30 referred to above. The 85 driving head is formed with an annular flange or lugs 33 in which are mounted the studs or arbors 34, shown as two in number, though more might be employed. Upon said arbors are journaled planetary gears 35 90 which are in mesh with the gear 32 referred to above. The upper end of the driving member 8' is reduced and threaded at 36 to receive a nut 37 and a reversing sleeve 38 is formed with an inwardly-extending flange 95 39 which surrounds the neck of the extension 36 and is held against vertical movement between the lugs 33 and nut 37 referred to above. Said sleeve is also formed with an 100 internal circular rack or gear 40 which engages the planetary gears 35 for a purpose to be presently described. The upper end of sleeve 25' is formed with an annular groove 105 41 and sleeve 38 carries two or more screws 42, the inner ends of which project into said groove to prevent relative axial movement between the sleeves 25' and 38.

When the chuck is applied to the spindle of a drill press and the latter is revolved, if there is no intervention on the part of the operator the chuck and tool carried thereby are revolved as in ordinary drill press operations. When it is desired to feed the tool downward the sleeve 25' is grasped and held from rotation so that the rotary movement 110 communicated by the drill spindle and driving member to the jaw-carrier feeds the latter downward as described in connection with the earlier-described form of the invention. In order to withdraw the drill or other tool from the work when desired, it is only necessary to grasp the reversing sleeve 38 115 leaving the sleeve 25' free to revolve. When this is done the continued revolution of the driving member carrying with it the planetary gears 35 causes the latter to roll upon the internal gear 40 and to thereby revolve the gear 32 carried by the sleeve 25'. By reason of the difference in diameters and 120 numbers of teeth between the internal gear 125

and the gear 32 the speed of the spindle is multiplied and the gear 32 and attached sleeve 25' driven in the same direction as but more rapidly than the driving member and the jaw-carrier. The result of this difference in speed is to cause such a relative rotation between the jaw-carrier and sleeve 25' as to cause the jaw-carrier to be fed upward by the threaded engagement between these elements. Obviously the speed of the upward feed is determined by the relative diameters of the gear 32 and the internal gear 40.

I claim:

1. A drill chuck comprising a jaw-carrier, a driving member adapted to be attached to the spindle of a drill, said driving member and jaw-carrier adapted and arranged for rotation together and for axial movement relative to each other, and a sleeve journaled with respect to one of said elements and having a threaded engagement with the other, the thread being so pitched that by holding the sleeve stationary the jaw-carrier will be fed downward.
2. In a chuck, a driving member, a jaw-carrier, connections between the same whereby they rotate together but are movable axially with relation to each other, the jaw-carrying member having a threaded portion and a member provided with a thread engaging the threaded portion of the jaw-carrier and adapted to revolve with the jaw-carrier or to be held stationary while the latter revolves.
3. In a chuck, a driving member, a jaw-carrier having telescopic connections therewith, said jaw-carrying member having also a threaded portion, an internally threaded member engaging the threaded portion of the jaw-carrier and adapted to revolve therewith or to be held stationary while the jaw-carrier revolves.
4. In a chuck, a driving member having a shank, a jaw-carrier having a bore to receive the shank and adapted to be revolved by the latter but to have axial movement relative thereto, said jaw-carrier having also an exteriorly threaded portion, a member having an internally threaded portion engaging the exteriorly threaded portion of the jaw-carrying member and adapted to revolve with the latter or to be revolved relatively thereto.
5. In a chuck, a driving member having a squared shank, a jaw-carrying member having an axial cavity squared in cross-section to receive said shank and an exteriorly threaded portion, an interiorly threaded sleeve engaging the threaded portion of the jaw-carrier, and connections between said sleeve and the driving member whereby rotary movement between the parts is permitted but axial movement prevented.
6. In a chuck, a driving member, a jaw-carrier engaging the same and revolved

thereby but movable axially with relation thereto, a portion of the jaw-carrier being exteriorly threaded, an exteriorly threaded sleeve engaging the exteriorly threaded portion of the jaw-carrier, and connections between said sleeve and the driving member whereby relative rotary movement is permitted but axial movement prevented. 70

7. In a chuck, a jaw-carrier, a driving member engaging and revolving the same, the connections between the two, however, permitting axial adjustment, the jaw-carrier being formed with an exteriorly threaded portion, an internally threaded sleeve engaging said threaded portion of the jaw-carrying member and revolvably suspended from the driving member. 75 80

8. In a chuck, a driving member having a squared shank with a reduced end, a jaw-carrying member having an axial bore fitting upon the non-cylindrical portion of the shank, said jaw-carrier having an exteriorly threaded portion, an internally threaded sleeve engaging said exteriorly threaded portion of the jaw-carrier and rotatably mounted upon the driving member but prevented from axial movement relative thereto. 85

9. In a chuck, a driving member adapted to be attached to a spindle and having an annularly grooved head and a squared shank terminating in a cylindrical portion, a jaw-carrying member having a squared axial bore adapted to receive said shank and formed with an exteriorly threaded portion, an interiorly threaded sleeve adapted to engage the threaded portion of the jaw-carrying member and having projections fitting within the groove of the driving member whereby rotation between the parts is permitted but relative axial movement prevented. 95 100 105

10. In a chuck, a driving member having a squared shank, a jaw-carrier having an axial cavity adapted to receive and fit said shank and an exteriorly threaded portion, said jaw-carrier also having a reduced portion likewise provided with an exterior thread, jaws supported from the jaw-carrier, a sleeve 19 interiorly threaded to engage the reduced portion of the jaw-carrier and having its interior diameter reduced at the lower end to coöperate with the jaws for forcing the same together, a sleeve having an interior thread for engaging the first said 110 115 threaded portion of the jaw-carrier, said sleeve having a revolvable engagement with the driving member. 120

11. In a chuck, a driving member, a jaw carrier engaging the driving member and revolvably therewith and axially movable with respect thereto, the jaw carrier being provided with an exterior thread, a handle member having an interior thread engaging the thread on the jaw carrier a reversing 125 130

sleeve and gearing between the reversing sleeve and handle member whereby by holding the reversing sleeve the handle member may be turned in the same direction as the 5 driving member.

12. In a chuck, a driving member, a jaw carrier rotatable with said driving member but adjustable axially with respect thereto, said jaw-carrying member being formed 10 with an exterior thread, an interiorly threaded hand sleeve engaging a thread on the jaw carrier, a reversing sleeve revolvably mounted with respect to the hand sleeve and driving member, gearing intermediate said 15 reversing sleeve and hand sleeve whereby when the reversing sleeve is held stationary the hand sleeve is revolved in the same direction as the driving member.

13. In a chuck, a driving member, a jaw carrier engaging and revolvble with said driving member but axially movable with relation thereto, said carrier having an exterior thread, a hand sleeve interiorly threaded and engaging the thread on the jaw carrier, a reversing sleeve revolvably mounted with respect to the driving member and hand sleeve, an internal annular gear on the reversing sleeve, an exterior gear on the hand sleeve and gears between the two 25 whereby when the reversing sleeve is held while the driving member is rotated, the hand sleeve will be rotated in the same direction as the driving member but at a greater rate of speed.

30 14. In a chuck, a driving member, a jaw carrier keyed upon the same for axial move-

ment with respect thereto, and having an exterior thread, a hand sleeve having an interior thread engaging the thread upon the jaw carrier, said sleeve also being formed 40 with a reduced portion, there being gear teeth upon said reduced portion, a reversing sleeve surrounding said reduced portion and having an internal gear formed thereon, and gears intermediate said internal and external gear and carried by said driving member, whereby rotation of the driving member relative to the reversing sleeve causes the hand sleeve to move in the same direction as said driving member but at a 50 greater speed.

15. A chuck comprising a driving member having a head and a squared shank, a jaw carrier having an opening fitting said shank whereby provision is made for relative axial 55 movement between the parts but rotative movement prevented, said jaw carrier being formed with an exteriorly threaded portion, a hand sleeve having an internal thread engaging the thread upon the jaw carrier and also reduced at one end and formed with a gear, two or more planetary gears mounted 60 upon the driving member and engaging the gear on the hand sleeve and a reversing sleeve connected to said driving member and hand sleeve and having an interior gear engaging the gears upon the driving member. 65

GUSTAV HALVORSEN-PANDE.
